(57) **CLAIM**

The ornamental design for a medical headlamp, as shown and described.

DESCRIPTION

FIG. 1 is a front left side perspective view of the medical headlamp; showing our new design.

FIG. 2 is a front right side perspective view thereof.

FIG. 3 is a top plan view thereof.

FIG. 4 is a left side view thereof.

FIG. 5 is a right side view thereof.

FIG. 6 is a left side view thereof; wherein the lamp is shown in the upper position.

FIG. 7 is a left side view thereof; wherein the lamp is shown in the lower position.

FIG. 8 is a rear view of FIG. 1; and,

FIG. 9 is a sectional view thereof.

In the drawings, the broken lines are for the purposes of illustrating environment only and form no part of the claimed design.
